EQUALIZER BEARING FOR PUMPERS

Clifford E. Anderson, Houston, Tex., assignor to
Emsco Derrick & Equipment Company, Los
Angeles, Calif., a corporation of California

Application May 6, 1941, Serial No. 392,063

10 Claims. (Cl. 74—41)

My invention relates to means for transmitting movement from a rotating power device to a reciprocating member, and relates particularly to a self-equalizing connection whereby a pumping lever or walking beam may be operated by a crank device having a pair of cranks which are connected to the walking beam through a pair of pitmans.

A long used practice in the art of pumping liquid from wells has been to reciprocate the walking beam by connecting it through a pitman to a crank mounted on an end of a crank shaft driven by some convenient source of power. As a crank, so used, is rotated, the forces transmitted from the shaft to the bearings supporting the same reverse during the upper and lower halves of the rotation of the crank. The resulting pounding action, where a single crank is used, is concentrated principally in the bearing adjacent the crank. It has been found that the crank structures employed in pumping devices may be materially lightened and greater useful life of the bearings may be obtained by employment of a pair of aligned, duplicate cranks mounted on the opposite ends of a crank shaft which is driven through suitable gearing connected to the central portion of the crank shaft. It is an object of the present invention to provide a simple and effective means for connecting dual cranks of this character to the walking beam or pumping lever of a pumping device of the general type employed to pump oil from oil wells.

It is a further object of the invention to provide a self-equalizing means for connecting the upper or far ends of the pitmans to the walking beam in such a manner that small variations in the dimensions of the cooperating parts and small disalignments of cooperating parts may be readily compensated for, and whereby the forces transmitted through the pitmans or connecting links will be equalized and accordingly the forces and reactions operating in the cranks and crank shaft bearings will be likewise equalized.

A further object of the invention is to provide in a device of the character set forth in the foregoing an equalizer member, made preferably in the form of a central fulcrum beam, having means for connecting the ends thereof to the pitmans, and having simple means for flexibly connecting the middle or intermediate portion of the equalizing member to the walking beam, whereby movement will be transmitted from the equalizing member through the flexible connection to the walking beam, and at the same time a relative swinging movement of the equalizing member

and the walking beam is permitted to compensate for small inaccuracies and dimensions in the formation and adjustment or assembly of the cooperating parts of the device. A further object of the invention is to provide an equalizing device of the character herein set forth comprising an equalizer beam having means for flexibly connecting the ends thereof to the pitmans and having a flexible member of a character to be deformed when forces are applied thereto, this flexible member operatively connecting the intermediate portion of the equalizer beam to the walking beam.

A further object of the invention is to provide 15 in an equalizing device of the character set forth in the preceding paragraph, means for connecting the intermediate portion of the equalizer beam to the walking beam comprising a body of rubbery material disposed so that it will serve to support the equalizer beam on the walking beam, and will permit a limited relative swinging movement of the equalizer beam and the walking beam while movement is being transmitted from the equalizer beam through the body of rubbery material to the walking beam. Herein I employ 20 the term "rubbery material" to mean a material having the general characteristics of rubber, rubber compound, or synthetic rubber, which is internally deformable by forces applied thereto 25 so that a change in shape will take place in the material in response to variations in the forces applied to the material.

A further object of the invention is to provide 30 an equalizer device of this general character wherein the equalizer beam is connected to the lever arm through use of a sleeve of rubbery material which substantially surrounds the intermediate portion of the equalizer beam, and a shell which surrounds at least a substantial portion 35 of the rubber sleeve, whereby operative connection is obtained with the lever arm.

A further object of the invention is to provide 40 a connection of the character set forth in the preceding paragraph wherein the shell surrounds three sides of the sleeve and clamps the remaining or fourth side of the sleeve to a part carried by the lever arm in such a manner that the rubbery material of the sleeve is placed under compression, thereby firmly gripping the intermediate portion of the equalizer beam, yet permitting a limited swinging movement of the beam to compensate for the factors of dimension, disalignment and adjustment hereinbefore referred to.

A further feature of the invention resides in 45 the provision of an interengagement between the

equalizer beam and the shell to limit relative movement of the equalizer beam and the shell in event of the failure of the sleeve of rubbery material, for the purpose which will be set forth later herein.

A further object of the invention relates to the provision of shock absorbing or cushioning means in a pumping device of the character disclosed. In a counterbalanced pumper, such as disclosed in the drawing, the direction of force transmission from the pitmans to the walking beam is reversed two times during each pumping cycle. The present invention provides means for cushioning the reversal stresses through a rubber body which likewise supports the lateral beam of the device for limited universal adjusting movement.

Further objects and advantages of the invention will be brought out in the following part of the specification.

Referring to the drawing which is for illustrative purposes only:

Fig. 1 is an elevational view showing a pumping apparatus employing a preferred embodiment of my invention.

Fig. 2 is an enlarged partly sectioned view, taken on a plane indicated by the line 2—2 of Fig. 1.

Fig. 3 is a fragmentary cross-section taken as indicated by the line 3—3 of Fig. 2.

Fig. 4 is a perspective view of the shell employed in the flexible connection of the equalizer beam to the pumping lever.

The environment in which my invention at present finds its principal use is in a pumping jack, such as shown in Fig. 1, wherein a pumping lever 10 is mounted by means of a bearing 11 at the upper end of a Samson post 12 so that it will swing in a vertical plane. A horse head 13 at the front end of the pumping arm 10, or walking beam, is connected to the upper end of a string of sucker rods 14. On the base 15 which carries the Samson post 12, a reduction gear case 16 is mounted, this reduction gear case having an input pulley 17 which may be driven by a suitable power source such as a motor 18 mounted also on the base 15. The power output shaft 19, carried by the case 16, has both ends thereof projecting so that upon each of these ends a crank 21 may be secured. The cranks, only one of which is shown in the elevational view, Fig. 1, are made in duplicate so that the effective lever arm of each crank will be the same. From the outer end of each crank 21, a pitman 22 is extended upward so that the upper or far ends of such pitmans will lie in the region of the rear portion of the pumping lever or walking beam 10.

To transmit reciprocating movement to the arm 10 from the pitmans 22, I provide a self-equalizing connection 23, which, as best shown in Figs. 2 and 3, comprises an equalizing member made preferably in the form of a beam tapering from the intermediate portion thereof toward the ends and having projecting trunnions 24 through which engagement of the beam 24 is made with the upper or far ends of the pitmans 22. The trunnions 24 support self-aligning bearings 25, the outer races 26 of which are contained in a bearing casing 27 secured by bolts 28 to the upper ends of the pitmans. The inner races of the bearings, as shown at 29, are spheroidal, so that the bearings 25 provide a flexible connection, within reasonable limits of the pitmans 22 with the ends of the equalizing beam 24. The lower, or near, ends of the pitmans 22 are con-

nected to the crank pins of the crank members 21 by self-aligning bearings 25', of the same type as shown, at the upper ends of the pitmans 22, in Fig. 2.

To flexibly connect the central portion of the equalizer beam 24 to the pumping lever or walking beam 10, I provide a body of rubbery material 31 in the form of a rectangular sleeve arranged to fit snugly around the intermediate portion of the equalizer beam 24, and to have operative connection with the pumping lever 10. As shown in Fig. 4, a casing 32 is provided, this casing having a shell which fits around three sides of the rubber sleeve 31. It has a top wall 33 and side walls 34 on the lower ends of which flanges 35 are formed. Lips 36 extend inward from the edges of the walls 33 and 34 to engage the end faces of the sleeve 31, these lips being of such size as to define openings 37 of larger area than the cross sectional areas of the portions of the equalizer beam 24 passing through these openings 37, thereby permitting a relative swinging movement of the equalizer beam 24 and the shell or casing 32 while movement is transmitted from the equalizer beam 24 through the sleeve 31 to the shell 32 and the pumping lever or walking beam 10.

For the purpose of maintaining the sleeve 31 in a centralized position relative to the equalizer beam 24, I have shown shallow notches 39 in the upper and lower faces of the intermediate portion of the equalizer beam 24 to receive the upper and lower portions of the sleeve 31. A feature of the invention is to so form the intermediate portion 40 of the equalizer beam 24, the sleeve 31 and the shell 32, that when the parts are assembled in the relation shown in Figs. 2 and 3, the rubbery material of the sleeve 31 will be under compression so as to tightly grip the intermediate portion of the equalizer member, yet permit swinging movement thereof. The upper and lower walls 42 and 43 of the sleeve 31 may be ordinarily placed under an initial compression substantially equal to the upward and downward force transmitted from the equalizer beam 24 to the shell 32 and the walking beam 10. The side walls of the sleeve 31 are made so that they will just slide into the space provided by the side walls 34 of the shell 32, but the vertical dimension of the sleeve 31 is made slightly greater than the vertical dimension of the space formed within the shell 32 by the side walls 34 and the top wall 33, with the result that when the sleeve and the intermediate portion of the equalizer beam 24 are assembled within the shell 32, the lower part of the sleeve 31 will project below the lower face of the flanges 35, and when the shell 32 is bolted onto the upper face of the walking beam 10, by use of bolts 45, the sleeve 31 will be placed under compression.

As shown in Fig. 3, the top flange 46 of the beam 10 has openings 47 spaced therealong to receive the bolts 45, and to enable the shell 32 to be secured in different positions along the walking beam 10, whereby the leverage or stroke of the front end 13 of the walking beam, shown as a horse head, may be varied without changing the cranks 21 but merely by shifting the connection 23 along the rear portion of the walking beam 10.

Interconnection of the shell 32 and the intermediate portion of the equalizer beam 24, to serve in the event of failure of the sleeve 31, is provided by a pin 48 which is passed through openings 49 in the intermediate portion 40 of the equalizer

member and the side walls of the sleeve 31, this pin 48 being of such length that the ends 50 thereof will engage vertical grooves 51 formed in the inner faces of the side walls 34, with a loose fit of the ends 50 in the grooves 51 so that equalizer beam 24 may swing relative to the shell 32. This slack means of interengagement between the equalizer member 24 and the shell 32 will function in event of failure of the sleeve 31 to prevent the equalizer beam from moving laterally relative to the beam 10 to such point that injury to the equipment may be caused.

I claim as my invention:

1. In a pumping device having a pumping lever, an equalizing member extending across the pumping lever and a pair of pitmans connected at the ends of the equalizing member: equalizing bearing means for said equalizing member and pumping lever comprising a resilient member connected to the intermediate portion of said equalizing member, there being means to connect said resilient member in cooperative relation to said pumping lever and said equalizing member so that movement may be transmitted through said resilient member from said equalizing member to said pumping lever, said equalizing member being supported by said resilient member so as to have clearance from said pumping lever and said connecting means to permit a circumductory swinging movement of said equalizing means relative to said pumping lever.

2. In a pumping device having a pumping lever, an equalizing member extending across the pumping lever and a pair of pitmans connected at the ends of the equalizing member: equalizing bearing means for said equalizing member and pumping lever comprising a flexible member engaging the intermediate portion of said equalizing member and said pumping lever, said flexible member embracing a body of rubbery material, there being means to hold said flexible member in cooperative relation to said pumping lever and said equalizing member so that movement will be transmitted from said equalizing member to said pumping lever and said equalizing member may have universal swinging movement relative to said pumping lever in consequence of the yielding of said flexible member.

3. In a pumping device having a pumping lever, an equalizing member extending across the pumping lever and a pair of pitmans connected at the ends of the equalizing member: equalizing bearing means for said equalizing member and pumping lever comprising a flexible member engaging the intermediate portion of said equalizing member and said pumping lever, said flexible member comprising a body of compressed rubbery material and means to hold said body in cooperative relation to said pumping lever and said equalizing member so that movement will be transmitted from said equalizing member to said pumping lever and said equalizing member may have universal swinging movement relative to said pumping lever in consequence of the yielding of said body.

4. In a pumping device having a pumping lever, an equalizing member extending across the pumping lever and a pair of pitmans connected at the ends of the equalizing member: equalizing bearing means for said equalizing member and pumping lever comprising a body of rubbery material having operative connection with an intermediate portion of said equalizing member and said pumping lever so that movement will be transmitted from said equalizing member to said pumping lever and so that said yielding of said body will enable universal and circumductory movement of said equalizing member around a point intermediate its ends, and means of interengagement between said

pumping lever and said equalizing member will be held from rotation about an axis extending from end to end thereof and will have freedom to swing relative to said pumping lever.

5. In a pumping device having a pumping lever, an equalizing member extending across the pumping lever and a pair of pitmans connected at the ends of the equalizing member: equalizing bearing means for said equalizing member and pumping lever comprising a body of rubbery material extending around at least three sides of an intermediate portion of said equalizing member, and a shell arranged to pass around and enclose at least a substantial portion of said body of rubbery material, said shell being formed so as to clear said equalizing member in such a manner that said equalizing member may have swinging movement relative to said pumping lever while said body of rubbery material transmits movement from said equalizing member to said pumping lever, and means for connecting said shell to said pumping lever.

6. In a pumping device having a pumping lever, an equalizing member extending across the pumping lever and a pair of pitmans connected at the ends of the equalizing member: equalizing bearing means for said equalizing member and pumping lever comprising a body of rubbery material encircling an intermediate portion of said equalizing member, and a shell arranged to pass around and enclose at least a substantial portion of said body of rubbery material, said shell being formed so as to clear said equalizing member in such a manner that said equalizing member may have swinging movement relative to said pumping lever while said body of rubbery material transmits movement from said equalizing member to said pumping lever, and means for connecting said shell to said pumping lever at different points therealong so that the effective lever arm of said pumping lever may be selectively varied.

7. In a pumping device having a pumping lever, an equalizing member extending across the pumping lever and a pair of pitmans connected at the ends of the equalizing member: equalizing bearing means for said equalizing member and pumping lever comprising a body of rubbery material extending around an intermediate portion of said equalizing member, and a shell arranged to pass around three sides of said body of rubbery material, said shell being formed so as to clear said equalizing member in such a manner that said equalizing member may have swinging movement relative to said pumping lever while said body of rubbery material transmits movement from said equalizing member to said pumping lever, and means for connecting said shell to said pumping lever.

8. In a pumping device having a pumping lever, an equalizing member extending across the pumping lever and a pair of pitmans connected at the ends of the equalizing member: equalizing bearing means for said equalizing member and pumping lever consisting of a body of rubbery material having operative connection with an intermediate portion of said equalizing member and said pumping lever so that movement will be transmitted from said equalizing member to said pumping lever and so that said yielding of said body will enable universal and circumductory movement of said equalizing member around a point intermediate its ends, and means of interengagement between said equalizing member and said shell to limit the

movement thereof in event of failure of said body of rubbery material.

9. In a pumping device having a pumping lever, an equalizing member extending across the pumping lever and a pair of pitmans connected at the ends of the equalizing member: equalizing bearing means for said equalizing member and pumping lever comprising a flexible member extending from the intermediate portion of said equalizing member to said pumping lever, there being means to hold said flexible member in cooperative relation to said pumping lever and said equalizing member so that movement will be transmitted from said equalizing member to said pumping lever and so that said yielding of said body will enable universal and circumductory movement of said equalizing member around a point intermediate its ends; and means to limit movement of said equalizing member relative to said pumping lever in event of failure of said flexible member.

10. In a pumping device having a pumping lever, an equalizing member extending across the pumping lever and a pair of pitmans connected at the ends of the equalizing member: equalizing bearing means for said equalizing member and pumping lever comprising walls of rubbery material at the intermediate portion of said equalizer beam and engaging the top, bottom, and lateral sides of said beam; a shell fitting closely around three of said walls and being adapted to clamp the remaining wall against said lever arm; and a pin extending through said equalizer beam and said sleeve so that the ends thereof will engage said shell so as to limit movement of said equalizer beam relative to said lever arm in event of failure of said sleeve of rubbery material.
